INDOOR STORM WINDOW AND SUNRAY MEMBER

Charles F. Flynn, Harrison, N. Y.

Application April 18, 1939, Serial No. 268,600

2 Claims. (Cl. 20—40)

This invention relates to new and useful improvements in an indoor storm window and sun-ray member.

The invention proposes the construction of an indoor storm window and sunray member characterized by a frame adapted to be mounted in a window frame on the inside of the sashes and provided with a member adapted to be extended thereacross.

Still further it is proposed to mount the member, which is preferably of Cellophane or other similar material, upon a roller mounted across the top of the frame and which is adapted to be moved downwards with its edges engaging grooves formed along the sides of the frame for holding the same in position and for preventing the shade from flapping in the wind.

Still further it is proposed to provide a novel means for locking the member in the frame and which is adapted to be opened to permit the member to be removed therefrom whenever desired.

As another object it is proposed to provide the frame with a means for holding the member in various extended positions across said frame.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure—

Figure 1 is an elevational view of a window frame having an indoor storm window and sunray member constructed according to this invention.

Fig. 2 is a vertical sectional view on the line 2—2 of Fig. 1.

Fig. 3 is a horizontal sectional view on the line 3—3 of Fig. 1.

Fig. 4 is a view similar to Fig. 3 illustrating the parts in their open position.

Fig. 5 is a sectional view on the line 5—5 of Fig. 1.

Fig. 6 is a sectional view on the line 6—6 of Fig. 1.

Fig. 7 is a perspective view of the indoor storm window and sunray member per se.

Fig. 8 is a view similar to Fig. 7 illustrating the parts in their open position.

Fig. 9 is a view similar to Fig. 2 but illustrating a modification of the invention.

Fig. 10 is a perspective view of the binding

strip used in conjunction with the modification shown in Fig. 9.

The indoor storm window and sunray member, according to this invention, is adapted to be used in conjunction with a window frame 10 of 5 conventional construction and having an outer sash 11 and an inner sash 12. The indoor storm window and sunray member includes a frame 13 which is normally engaged into the window frame 10 on the inside of the sashes 11 and 12, 10 as shown in Fig. 2. A means is provided for removably holding the frame 13 in position within the frame 10 and comprises a plurality of lugs 14 pivotally supported upon the window frame 10. These lugs 14 are adapted to be extended 15 across the edge of the frame 13, as shown in Figs. 1 and 3, for removably holding the frame 13 in position within the window frame 10.

A roller 15 having a ray member 16 is removably mounted across the top of the frame 13. 20 One end of the roller 15 is provided with a pin which engages into a circular bracket 17 mounted upon one side of the frame 10. The other end of the roller 15 is provided with a turnable lug which engages a slotted bracket 18 mounted on 25 the other side of the frame 13. The turnable lug of the roller 15 is provided with a spring means for causing the roller to be returned to its normal position after the member has been extended and again released. This roller 15 is 30 similar in construction to conventional window shade rollers except that it does not have the catch which permits the roller to be stopped at any desired position.

A top strip 19 is hingedly mounted across the 35 top of the frame 13. This hinged mounting is accomplished by a pair of hinges 20 mounted upon the adjacent portions of the top strip 19 and the top portion of the frame 13. This top strip 19 is adapted to extend downwards over the roller 15 to shield the roller from being removed. Side strips 21 are hingedly mounted on the sides of the frame 13. This hinged mounting is accomplished by means of hinges 22 mounted on the adjacent portions of the side strips 21 and the frame 13. The top ends of the side strips 21 are provided with upwardly extending top fingers 23 which engage over the ends of the top strip 19 for locking the top strip in its operative position when the side strips are 40 45 50 55 in their inwardly hinged position.

A bottom strip 24 is hingedly mounted across the bottom of the frame 13. This hinge construction is accomplished by means of hinges 25 mounted upon the adjacent faces of the bot- 55

tom strip 24 and the frame 13. The bottom strip 24 has end portions 24^a and in one position of the bottom strip these end portions are adapted to engage over the bottom ends of the side strips 21 for locking them in their inwardly hinged position.

The strips 19, 21, and 24 are padded at 19', 21' and 24', respectively, to keep the storm window air proof.

10 A means is provided for locking the bottom strip in a position in which it will hold the side strips 21 in their inwardly hinged position. This means comprises a stud 26 rotatively extended through the bottom strip 24. The frame 13 is 15 provided with a cutout portion covered by means of a plate 27 having an opening 28 into which the bottom end of the stud 26 extends. This stud extends into the opening 28 when the bottom strip 24 is in its inwardly hinged position.

20 The bottom end of the stud 26 is provided with a pin 29 extending at right angles thereto and alignable with offset portions 28^a formed on the sides of the opening 28. The top end of the stud 26 is provided with a handle 30 which is 25 adapted to be used for turning the stud to align and disalign the pin with relation to the offset portions 28^a for permitting the bottom strip 24 to be moved to the open position as shown in Fig. 8, or be locked in its inwardly hinged position as shown in Fig. 2.

30 Stationary strips 31 are mounted upon the frame 13 slightly spaced rearwards from the side strips 21 and the bottom strip 24 for forming grooves 32. These strips 31 are held in position by means of nails 33 which extend through the strips 31 and into the frame 13. The side edges of the ray member 16 which is constructed of Cellophane or other similar transparent material, has its edges normally extended into the grooves 32 at the sides of the frame 13 as shown in Fig. 3.

35 The free end of the ray member 16 is provided with a binding strip 34 which also has its ends engaging the grooves 32 formed at the sides of the frame 13. This binding strip 34 on its inner 40 face is provided with an upwardly extending handle portion 34^a which is adapted to be used for moving the strip 34 downwards for extending the ray shade 16 across the frame 13. It is proposed that the bottom strip 24 be in its open position while the binding strip 34 is being moved downwards. The inner face of the binding strip 34 is provided with inwardly extending lugs 34^b which are adapted to engage complementary cutouts 24^b formed in the inner bottom corners of the bottom strip 24. Thus when the binding strip 34 is in its completely down position, as shown in Fig. 2, and the bottom strip 24 is again pivoted to its closed position and locked therein, the lugs 34^b will engage the cutouts 24^b and maintain the strip 34 in its down position against the action of the spring in the roller 16. When the strip 24 is again moved to its open position the spring in the roller 16 will 50 tend to draw the binding strip 34 back to its normal position and wind the ray member 16 thereon.

55 At the extremities of the binding strip 34, vertical extensions 34^c are provided for smoothly guiding the member 16 up and down.

The operation of this form of the invention is as follows:

60 The frame 13 is engaged into the window frame 10 and the lugs 14 are extended to engage the edges of the frame 13 to hold the frame 13 in position within the window frames 10. The roller 16 having the ray member 16 wound thereon is open across the top portion of the frame 13 by engaging the pin into the bracket 17 and the lug 18 thereof into the slotted bracket 18. The top strip 19 is then pivoted to its closed position to shield the roller 16 against being removed. The side strips 21 are then pivoted to their closed position to cause the fingers 23 to engage the ends of the top strip 19. The bottom strip 24 is then pivoted to its closed position and locked therein for completing the position of the storm window and sunray member in position within the frame 10.

65 If it is desired to extend the ray member 16 the bottom strip 24 is moved to its open position and the handle 30 on the binding strip 34 is used to move the strip and member downwards within the grooves 32 formed at the sides of the frame 13. When the binding strip 34 reaches its completely down position the strip 24 is again pivoted to its closed position to cause the cutouts 24^b to engage the lugs 34^b to hold the strip and member in its down position. This movement of the strip 34 causes the spring within the roller to become taut, and when the bottom strip 25 is again moved to its open position this spring will tend to draw the member and strip back to their normal position.

70 According to the modification of the invention shown in Figs. 9 and 10 the construction of the indoor storm window and sunray member is similar to that previously described, except for the provision of a means for holding the binding strip 34' of the sunray member 16 in various extended positions across the frame 13 as shown in Fig. 9. To accomplish this the inner face of the side strips 21 are provided with a plurality of rack teeth 21^a. The ends of the binding strip 34^a have inwardly extending leaf springs 34^c which are adapted to engage the teeth 21^a for limiting upward movement thereof when the strip 34 is extended to a position intermediate the top and bottom ends of the frame 13. For releasing the strip 34' to permit the member 16 and the strip to move back to their normal up positions it is necessary to move the side strips 21 to their open position to disengage the teeth 21^a from the leaf spring 34^c. In other respects this form of the invention is similar to the previous form.

75 It is to be understood that this sunray member 50 may be made of Cellophane or any other suitable transparent flexible material and when used in connection with an open window permits the ultra violet rays of the sun to penetrate through the same, into the room, with the same beneficial 55 result one would obtain in the open air. It is known that glass breaks down and excludes the health rays of the sun.

80 While I have illustrated and described the preferred embodiments of my invention, it is to be understood that I do not limit myself to the precise constructions herein disclosed and the right is reserved to all changes and modifications coming within the scope of the invention as defined in the appended claims.

85 Having thus described my invention, what I claim as new, and desire to secure by United States Letters Patent is:

1. An indoor storm window and sunray member, comprising a frame adapted to be mounted in a window frame, a roller with a "ray" member removably mounted across the top of said frame, a top strip hingedly mounted across the top of said frame and adapted to shield said roller from being removed, side strips hingedly mounted on 75

- the sides of said frame and having top fingers engaging over the ends of said top strip for locking said top strip when said side strips are in inwardly hinged positions, a bottom strip hinged-
5 ly mounted across the bottom of said frame and having end portions in one position thereof en-
gaging over the bottom ends of said side strips in
the latter positions thereof for locking same in
position, means for locking said bottom strip in
10 said one position, stationary strips mounted on
said frame spaced slightly rearwards of said
hinged strips forming grooves, and the edges of
said member being engaged in said grooves, said
means comprising a stud normally extended
15 through said bottom strip and alignable with
an opening formed in the bottom of said frame,
and a plate extended across the opening in said
frame and having an opening through which said
stud extends, a pin extended through said stud
20 at right angles thereto, offset portions formed at
the sides of the opening in said plate, and a
means for aligning and disaligning said pin with
relation to said offset portions for permitting said
bottom strip to be moved to an open or closed
25 position.
2. An indoor storm window and sunray mem-
ber, comprising a frame adapted to be mounted
in a window frame, a roller with a "ray" member
removably mounted across the top of said frame,
a top strip hingedly mounted across the top of
said frame and adapted to shield said roller from
being removed, side strips hingedly mounted on
the sides of said frame and having top fingers
engaging over the ends of said top strip for lock-
ing said top strip when said side strips are in
inwardly hinged positions, a bottom strip hinged-
5 ly mounted across the bottom of said frame and
having end portions in one position thereof en-
gaging over the bottom ends of said side strips in
the latter positions thereof for locking same in
position, means for locking said bottom strip in
10 said one position, stationary strips mounted on
said frame spaced slightly rearwards of said
hinged strips forming grooves, and the edges of
said member being engaged in said grooves, said
roller being provided with a spring tending to
15 draw said member back to its normal position
when extended across said frame, and a means
for holding said member in its extended position
against the action of said spring, said means com-
prising a binding strip mounted on the free edge
20 of said member, cutout portions formed in the
bottom inner corners of said bottom strip, and
inwardly extending lugs formed on said binding
strip and engageable into said cutouts when said
bottom strip has been opened and again closed
25 for holding said member in its extended position.

CHARLES F. FLYNN.
